HIS ATTORNEY.

UNITED STATES PATENT OFFICE.

ORLEN HOBSON, OF FRESNO, CALIFORNIA.

APPAREL LACING.

1,416,203.

Specification of Letters Patent. Patented May 16, 1922.

Application filed May 21, 1921. Serial No. 471,301.

To all whom it may concern:

Be it known that I, ORLEN HOBSON, a citizen of the United States, and resident of Fresno, in the county of Fresno and State 5 of California, have invented certain new and useful Improvements in Apparel Lacing, of which the following is a specification.

My invention relates to a device designed 10 to take the place of the present eyelets in shoes and all other garments where lacing is used to fasten the same, and the object thereof is to provide a cheap, simple and efficient device for that purpose.

Heretofore in the use of lacing for securing 15 garments such as shoes and the like where eyelets are used, in drawing the lacing tight enough to properly fasten the garment, owing to the overlapping of the laces 20 on the edge of the eyelet, a pressure was exerted downwardly causing the laces to press upon the portion of the body covered thereby which was both inconvenient and uncomfortable, and one of the objects of my invention 25 is to provide a lace fastening in which the pull exerted by the laces will be in a direct line with the edge of the garment, thus preventing the above mentioned objections to the present form of lacing.

Another object is to provide a device of 30 the above character which can be easily and quickly positioned for use without the use of special tools.

Other objects and advantages will appear 35 hereinafter and while I have shown and will describe the preferred form of my invention, I wish it to be understood that I do not limit myself to such preferred form but that various changes and adaptations may be 40 made therein without departing from the spirit of my invention, and while I have shown my device as applied to shoes, I do not limit myself to such particular use but claim the right to use the same as a fastening 45 wherever laces are used at the present time.

In the drawings accompanying and forming 50 a part hereof:

Fig. 1 is a front elevation of a shoe constructed according to my invention.

Fig. 2 is an enlarged perspective view of one form of eyelet.

Fig. 3 is a side elevation of one of my eyelets on an enlarged scale in its position of 55 use with a fragment of a shoe.

Figs. 4 and 5 are an end elevation and

side elevation respectively of another form of eyelet.

Fig. 6 is a front elevation of fragments of a shoe with my improved fastener and lacing thereon positioned for use. 60

Referring to the drawings, 6 represents a shoe of usual construction on the front closure edges 7 and 8 of which are mounted my eyelets 9. As shown in Figure 2 my eyelets 65 comprise a vertically extending tubular portion 10, the interior opening 11 of which is tapered at each end outwardly as a means for free access for the lace in threading the same, and also acts to prevent the lace being 70 damaged by the edges of said opening. Extending from the outer periphery of eyelet 9 is an attaching member 12 provided at its end with a right angle prong 13 and on each edge, intermediate the ends, are also provided similar prongs 14 and 15. In positioning this form of eyelet the prongs are projected through the material forming the shoe, from the inner side so that the inner edge of the eyelet will be in alignment with 75 the closure edges of the shoe. These prongs are then clamped downwardly to lie parallel with the outer surface of the shoe and thereby prevented from displacement.

In the form shown in Figs. 4 and 5 my device 80 comprises an eyelet 16 similar in all respects to eyelet 9 and has projecting from the side thereof a securing member 17. Member 17 comprises a narrow neck 18 adjacent to the eyelet 16 and is then widened 85 a short distance and is then tapered towards its end inwardly in substantially arrowhead shape. In positioning this form of my device for use a strip of leather or like material 19 is provided which is doubled or 90 folded upon itself and has slits 20 cut at the junction or fold of a width substantially the same as the width of neck 18. The tapered portion of member 17 is forced through the slit until the neck 18 is within the slit, the 95 enlarged portion of member 17 preventing withdrawal of the device. The free ends of the folded portions are then positioned on 100 each side of the closure portions of the shoe and secured in place by stitching or otherwise.

In the use of my device the parts will be positioned as shown in Figure 1. The laces will be extended therein in the usual manner and the shoe is laced in the same manner as 110 at present, the advantage in my invention being that less strain is placed upon the lace

and the pull exerted by the lace is in a direct line with the closure edges of the shoe.

Having described my invention what I claim is:

- 5 1. An eyelet fastening for garments comprising a tubular eyelet adapted to be secured to the abutting edges of the portions to be drawn together; holding means for said eyelet comprising a projection extending from the side of said eyelet and being substantially arrowhead shaped in side elevation, and being provided, at its connection to said eyelet, with a narrowed neck.
- 10 2. In a fastening for shoes and the like the combination of a strip of flexible material adapted to be folded upon itself longitudinally and to have its free ends secured upon opposite sides of each of the parts to be drawn together and being provided in its folded portion with a plurality of narrow

slits extending longitudinally thereof; and a plurality of tubular eyelets each provided with an arrow-head shaped projection extending from the side thereof, said projection being provided at its connection to said eyelet with a narrowed neck adapted to be mounted within said slits, said enlarged portion serving to prevent withdrawal thereof, there being one of said eyelets for each of said slits; and a single lacing within said eyelets, said lacing having its central portion extending between the lowermost eyelets and having its free ends extending through alternate eyelets on the opposed portions to be drawn together.

In witness that I claim the foregoing I have hereunto set my hand this 14th day of May, 1921.

ORLEN HOBSON.
